UNITED STATES PATENT OFFICE.

JAMES C. H. VAUGHT, OF NEW YORK, N. Y.

POWER-DRILL.

1,340,468.

Specification of Letters Patent. Patented May 18, 1920.

Application filed December 6, 1917. Serial No. 205,711.

To all whom it may concern:

Be it known that I, JAMES C. H. VAUGHT, a citizen of the United States, residing at New York, in the county and State of New 5 York, have made a certain new and useful Invention in Power-Drills, of which the following is a specification.

This invention relates to power drills, and particularly to the class which uses a shell 10 or support and a feed screw with which the machine is fed forward to its work during the drilling operation.

The object of the invention is to provide a power drill which is simple in construction 15 and efficient in operation.

A further object of the invention is to provide a feed attachment which may be applied to standard types of power drills.

A further object of the invention is to provide 20 a feed apparatus for a drill of the class described whereby a machine may be fed forward by means of the usual feed screw, and in addition thereto to provide a means to render the feed screw inoperative when it 25 is necessary to return the machine to its rearward or retracted position. The object of rendering the usual feed screw inoperative when it becomes necessary to return the same to its retracted position is to save time 30 which with the present type of power drills is now lost in forcing the machine rearwardly.

Further objects of the invention will appear more fully hereinafter.

The invention consists substantially in the construction, combination, location, and relative arrangement of parts, all as will be more fully hereinafter set forth as shown in the accompanying drawing, and finally 40 pointed out in the appended claims.

Referring to the drawings:—

Figure 1 is a view in side elevation, partly in section, of a drill embodying my invention.

45 Fig. 2 is a longitudinal sectional view of the feed control apparatus employed in accordance with my invention.

Fig. 3 is a sectional view taken on the line 3, 3, Fig. 2, looking in the direction of 50 the arrows in a reduced scale.

Fig. 4 is a side elevation of the usual feed screw.

Fig. 5 is a top plan view of the inclined plane member indicated by reference 55 numeral 4, Fig. 1.

Fig. 6 is a top plan view of a handle used on the inclined plane member.

Fig. 7 is a cross section of the same taken on the line 7—7, Fig. 2, and looking in the direction of the arrows.

60

Fig. 8 is a side elevation of the same.

Fig. 9 is a side elevation of the inclined plane member 17.

Fig. 10 is a top plan view of a portion of the shell or support, shell rods, feed 65 screw, yoke, and crank, disassembled from the machine proper.

Fig. 11 is an end view of the yoke shown at numeral 8, Fig. 10.

Fig. 12 is a bottom view of the gib which 70 meshes with the feed screw.

Fig. 13 is a top plan view of the gib.

Fig. 14 is a sectional view taken on the line 9, 9, Fig. 17, and looking in the direction of the arrows.

75

Fig. 15 is a rear view of the gib.

Fig. 16 is a view in section showing a slightly modified form of construction embodying my invention.

Fig. 17 is a top plan view of the housing. 80

Fig. 18 is a side elevation of the gib.

Fig. 19 is a top view of a tube and jam nut which is rigidly secured to the cylinder of the machine.

The same part is designated by the same 85 reference numeral wherever it occurs throughout the several views.

In the construction of mounted power 90 drills using a shell or support it is the usual custom to supply such machines with a feed screw to feed the machine forward during the drilling operation, and by the use of the same feed screw it is the practice to return the same to its initial position. The forward and rearward movement of the machine is made possible in machines now in common use by providing the cylinder of the machine with an eye on the under side of the machine and at the rear end of the cylinder. Into this eye is placed what is 95 commonly called a feed nut which projects beyond the eye of the cylinder, and on the projecting portion of the feed nut it is the practice to provide a jam nut, the purpose of the jam nut being to hold the cylinder and the feed nut in rigid unison. It is obvious that the feed nut must be provided with a threaded screw within its interior in which the usual feed screw moves when the machine is being fed forward as well as 105

100

Fig. 2 is a longitudinal sectional view of the feed control apparatus employed in accordance with my invention.

Fig. 3 is a sectional view taken on the line 3, 3, Fig. 2, looking in the direction of 50 the arrows in a reduced scale.

Fig. 4 is a side elevation of the usual feed screw.

Fig. 5 is a top plan view of the inclined plane member indicated by reference 55 numeral 4, Fig. 1.

110

when it is being returned or retracted to its rearward position. It is apparent that the forward movement of the machine during the drilling operation is very slow and cannot be speeded beyond the cutting capacity of the drill bit. It is likewise apparent that in returning the machine to its initial or rearward position the operation is as slow as the maximum speed that can be attained in advancing the machine, and consequently the loss of much time is the inevitable result. In power drilling work where efficiency is to be maintained any time wasted such as is required to return the machine to its retracted position is objectionable. With a view of overcoming particularly this objection it is the purpose of my present invention to design and devise a means to feed a machine forward and to allow the machine to be retracted quickly. Another advantage of my invention is that the control of the feed apparatus renders it possible to advance the machine forwardly as far as desired without necessitating the use of said screw. The advantage of this is that when the machine has been forced to its rearward position for the purpose of changing the drill steels it is necessary that when the new drill steel has been adjusted the same is at a distance from the rock, and with the machines now in use the slow tedious feeding of the machine by means of the feed screw forward until the drill bit is in contact with the rock causes an additional loss of time. While I have shown and will now describe my invention as forming a part of a complete machine I wish it to be understood that the same may form an attachment which may be readily applied to all machines now in use. In accordance with my invention I provide a hollow tube 11 like that shown in Fig. 19, the same having a smooth inner surface. This tube I insert in the eye of the machine 10. On the exterior of the tube I provide a thread to receive the jam nut 12. On the outer end of the tube I secure a housing 13 shown in Fig. 17. In said housing I provide an oblong slot 14 which communicates with the oblong slot in the tube 15. Within such slot is inserted a gib like that shown in Figs. 12, 13, 15, and 18, and designated by reference numeral 16. To this gib I apply an inclined plane member 17, on the outer end of which is secured the handle 5. Within the top of the gib is placed a spiral spring 18 to exert a pressure between the gib and the surrounding band to force the gib in engagement with the feed screw. Surrounding the housing is a band 19, the purpose of which is to hold the several parts in unison as will be readily understood. In Fig. 10 I show an embodiment of a part of the shell or support 20, the shell rods being indicated at 21, the feed screw at 22, the crank at 23, and the yoke at 24.

The cylinder and machine proper are assembled with the several parts composing Fig. 10 as is clearly shown in Fig. 1. Fig. 11 shows a yoke 8 which is secured to the rear end of the shell rods and in which the rear end of the feed screw journals. Figs. 12, 13, 15, and 18, show different views of the gib which is forced to mesh with the feed screw by means of the spiral spring 18, said gib being forced out of engagement with the feed screw by means of the inclined plane member 17 when the same is pulled backward into the position shown in full lines Fig. 2. In practice when it becomes necessary to force the machine to its rearward position the operator forces the inclined plane member 17 to its farthest rearward position as shown in Fig. 1 thereby lifting the gib out of engagement with the feed screw. When it is desired to feed the machine forwardly and slowly during the drilling operation the operator forces the inclined plane member 17 to its farthest forward position as shown in dotted lines 25, Fig. 2, thus allowing the gib to engage with the feed screw, whereby upon rotation of the feed screw the machine is fed forwardly. Within the housing, and preferably at one corner thereof, I provide a hole to receive the spiral spring on top of which is placed a metal ball 27, the ball and spring being imprisoned by slightly battering the orifice of the hole to retain the same therein and at the same time to allow the ball to yieldingly protrude slightly beyond the top surface of the housing against the action of the spring. When the inclined plane is forced to its rearward position the ball will rest in a duck's nest formed on the under side of the inclined plane 28 which will act as a locking medium to hold the inclined member 17 in position, and therefore keep the threaded gib out of mesh with the feed screw when it is necessary to force the machine quickly to its rearward position or to allow the machine to be forced quickly forwardly to operative position. In Fig. 16 I show a slightly modified form of construction wherein instead of completely surrounding the housing and gib with a band I provide a U-shaped clevis which partly surrounds the housing, as well as the several other parts, and which are all held in unison by means of a transverse pin 30.

From the foregoing it will be apparent that I have provided a rock drilling machine attachment which allows the machine to be fed forward in the usual manner of slow feed and at the same time to render the feed screw inoperative to allow a quick retraction of the machine or a quick forward feed of the machine to its operative position, and wherein the operation is performed by hand in a small fraction of the time now required for similar purposes by the usual feed screw.

method which is the universal type of power drill mechanism now employed. While I have shown and described specific structures which accomplish the purpose of my invention 5 I wish it to be understood that many modifications and variations in details will readily occur to those skilled in the art without departing from the spirit and scope of my invention as defined in the claims, and I 10 therefore desire that the foregoing specific structures be interpreted in an illustrative sense rather than in a limiting sense.

Having now set forth the objects and nature of my invention, and having shown 15 and described in detail structures embodying the principles thereof, what I claim as new and useful and of my own invention, and desire to secure by Letters Patent, is—

1. In a rock drilling machine of the 20 mounted type, an eye or opening in the rear end of the cylinder of the machine, a tube located in said eye and having a smooth inner surface and a threaded outer surface, means for holding the tube and cylinder in 25 rigid unison, a feed screw located in said tube, a housing located on said tube and provided with a slot, a gib located in said slot, a band surrounding the housing and 30 gib to hold the same in unison, and means to raise and lower the gib.

2. In a rock drilling machine of the 35 mounted type, an eye or opening in the rear end of the cylinder of the machine, a tube located in said eye and having a smooth inner surface and a threaded outer surface, means for holding the tube and cylinder in 40 rigid unison, a feed screw located in said tube, a housing located on said tube and provided with a slot, a gib located in said 45 slot, a band surrounding the housing and gib to hold the same in unison, means to raise and lower the gib, and means to lock the gib in its raised position.

3. In a rock drilling machine, a shell or 50 support, said machine being carried by said support, and having an eye in its rear end, a tube passing through said eye and having a smooth inner surface and threaded outer surface, means for holding the tube and cylinder in rigid unison, a housing carried by said tube, a slot in said housing and tube, a gib located therein, an inclined plane member 55 engaging said gib to raise and lower the same, and a band surrounding said housing, gib, and inclined plane member to hold the parts in unison.

4. In a rock drilling machine of the 60 mounted type, an eye or opening in the rear end of the cylinder of the machine, a tube located in said eye and having a smooth inner surface and a threaded outer surface, means to hold the tube and cylinder in rigid 65 unison, a feed screw located in said tube, a housing carried by said tube, a slot located in said housing and tube, a threaded gib

located in said slot, a band surrounding the housing and gib, a spring located between the band and gib and normally tending to force the gib to mesh with the feed screw while the machine is being fed forward during the drilling operation thereof, and means to raise the gib out of meshing engagement with the feed screw. 70

5. In a rock drilling machine of the mounted type, an eye or opening in the rear 75 end of the cylinder of the machine, a tube located in said eye and having a smooth inner surface and a threaded outer surface, means to hold the tube and cylinder in rigid unison, a feed screw located in said tube, a 80 housing carried by said tube, a slot located in said housing and tube, a threaded gib located in said slot, a band surrounding the housing and gib, a spring located between the band and the gib and normally tending 85 to force the gib to mesh with the feed screw while the machine is being fed forward during the drilling operation thereof, means to raise the gib out of meshing engagement with the feed screw, and means for locking 90 said gib in its raised position.

6. In a rock drilling machine of the mounted type, a tube secured to the rear end 95 of the cylinder of said machine, said tube having a smooth inner surface, a feed screw located within said tube, a housing carried by said tube, a slot in said housing and tube, a gib located in said slot, said gib being provided with threads to mesh with said feed screw, means normally tending to force the 100 gib to engage with said feed screw, and means to disengage the gib from said feed screw.

7. In a rock drilling machine of the mounted type, a tube secured to the rear end 105 of the cylinder of said machine, said tube having a smooth inner surface, a feed screw located within said tube, a housing carried by said tube, a slot in said housing and tube, a gib located in said slot, said gib being provided with threads to mesh with said feed screw, means normally tending to force the 110 gib to engage with said feed screw, means to disengage the gib from said feed screw, and means for locking said gib in its disengaged 115 relation relative to said feed screw.

8. In a rock drilling machine of the mounted type, a cylinder, a tube secured to said cylinder, a feed screw carried by said tube, a housing secured to said tube, a gib 120 located in said housing, said gib provided with means to engage said feed screw to travel along same in one direction or the other when said feed screw is rotated, and means for disengaging said gib from said 125 feed screw.

9. In a rock drilling machine of the mounted type, a cylinder, a tube secured to said cylinder, a feed screw carried by said tube, a housing secured to said tube, a 130

- gib located in said housing, said gib provided with means to engage said feed screw to travel along same in one direction or the other when said feed screw is rotated, means 5 for disengaging said gib from said feed screw, and means for locking said gib in its disengaged relation relative to said feed screw.
10. In a rock drilling machine of the mounted type, a cylinder, a tube secured to said cylinder, a feed screw carried by said tube, a housing secured to said tube, a slot located in said housing and tube, a gib located in said slot, said gib being concaved 15 on its lower face and provided with threads adapted to mesh with said feed screw, and means for forcing said gib out of engagement with the feed screw.
11. In a rock drilling machine of the mounted type, a cylinder, a tube secured to said cylinder, a feed screw carried by said tube, a housing secured to said tube, a slot located in said housing and tube, a gib located in said slot, said gib being concaved 25 on its lower face and provided with threads adapted to mesh with said feed screw, means for forcing said gib out of engagement with the feed screw, and means for locking said gib out of engagement with said feed screw.
30. 12. In a rock drilling machine of the mounted type, a cylinder, a tube secured to said cylinder, a feed screw carried by said tube, a housing secured to said tube, a gib located in said housing, said gib being concaved 35 on its lower face and said face being provided with threads adapted to mesh with said feed screw, and means for disengaging said gib from said feed screw.
13. In a rock drilling machine of the mounted type, a cylinder, a tube secured to said cylinder, a feed screw carried by said tube, a housing secured to said tube, a gib located in said housing, said gib being concaved 45 on its lower face and said face being provided with threads adapted to mesh with said feed screw, means for disengaging said gib from said feed screw, and means for locking said gib in its disengaged position.
50. 14. The combination with a rock drilling machine having an eye or opening in the rear end of the cylinder thereof, of a tube located in said eye, said tube having a smooth inner surface and a threaded outer surface, means for holding the tube and cylinder in rigid unison, a housing on the outer end of said tube, a slot located in said housing and tube, a threaded gib carried in said slot, said gib having V-shaped 55 grooves on each side thereof, a movable inclined plane member working in said grooves to raise and lower said gib and means for moving said inclined plane member.
15. The combination with a rock drilling machine having an eye or opening in the rear end of the cylinder thereof, of a tube located in said eye, said tube having a smooth inner surface and a threaded outer surface to receive a jam nut to hold the tube and cylinder in rigid unison, a housing on the outer end of said tube, a slot in said housing and tube, a threaded gib in said slot, said gib having V-shaped grooves on each side thereof, a movable inclined plane member working in said grooves to raise and lower said gib, a spring located within the wall of the housing, a ball carried by said spring and projecting above the surface of the housing, a depression located on the under surface of the inclined plane member, and adapted to coöperate with said ball to lock the movable inclined plane member when the latter is forced to its extreme rearward position.
16. In a rock drilling machine of the mounted type, a tube rigidly secured to the cylinder of said machine, a housing secured to said tube, a slot located in said housing, a gib carried in said slot and provided at its lower end with threads, a feed screw carried in said tube, the threads on said feed screw and gib meshing together while the machine is being fed forward, means for exerting a yieldable tension against the gib to hold it in mesh with said screw, a movable inclined plane member working in said housing to force the gib out of mesh with the feed screw when moved in its rearward position.
17. In a rock drilling machine of the mounted type, a tube rigidly secured to the cylinder of said machine, a housing secured to said tube, a slot located in said housing, a gib carried in said slot and provided at its lower end with threads, a feed screw carried in said tube, the threads on said feed screw and gib meshing together while the machine is being fed forward, means for exerting a yieldable tension against the gib to hold it in mesh with said screw, a movable inclined plane member working in said housing to force the gib out of mesh with the feed screw when moved in its rearward position, and means for locking the inclined plane member in its rearward position.

In testimony whereof I have hereunto set my hand on this 3rd day of December, A. D. 1917.

JAMES C. H. VAUGHT.
